Primary Examiner — Eric L Goodman*Assistant Examiner* — Kyle A. Edelmaier(74) *Attorney, Agent, or Firm* — JEEN IP LAW, LLC(57) **CLAIM**

The ornamental design for a neck fan, as shown and described.

DESCRIPTION

FIG. 1 is a front, right and top perspective view of a neck fan, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 of FIG. 2 thereof; and,

FIG. 10 is a schematic diagram showing the neck fan in the unfolded state.

The dot-dash broken lines depict the boundaries of the enlargements that form no part of the claimed design.

1 Claim, 10 Drawing Sheets(56)
